UNITED STATES PATENT OFFICE.

GEORGE ASHWORTHII AND ELIJAH ASHWORTHII, OF MANCHESTER, COUNTY OF LANCASTER, ENGLAND.

DRIVING MECHANISM FOR CARDING-ENGINES.

SPECIFICATION forming part of Letters Patent No. 403,720, dated May 21, 1889.

Application filed October 5, 1886. Serial No. 215,386. (No model.) Patented in England August 2, 1884, No. 10,881.

To all whom it may concern:

Be it known that we, GEORGE ASHWORTH and ELIJAH ASHWORTH, subjects of the Queen of Great Britain and Ireland, residing at 5 Manchester, county of Lancaster, England, have invented certain Improvements in Driving Mechanism for Carding-Engines, (for which British Letters Patent No. 10,881 were granted under date of August 2, 1884,) of 10 which the following is a specification.

Our invention relates to the driving of the doffer and main cylinder during the process of grinding. In the ordinary method of driving during the grinding the cylinder receives 15 motion under the working conditions and revolves at its working speed, while the speed of the doffer is accelerated so as to have about the same surface speed as the main cylinder. In order to obtain a better grinding effect, we so arrange the driving of the doffer as that during grinding its surface speed shall be reduced, and we also provide 20 suitable means for reducing the surface speed of the main cylinder to a corresponding extent. 25

In the accompanying drawings, Figure 1 is a side elevation of sufficient of a carding-engine to illustrate our improvements. Fig. 2 is a plan of the parts on the same side of the 30 cylinder. Figs. 3 and 4 are corresponding views on the other side of the cylinder, and showing devices which may be employed for driving the main cylinder from the doffer. Fig. 5 is a sectional view illustrating the construction of a detail of the machine. 35

A is the main cylinder, having its shaft A' adapted to suitable bearings, as usual, in the frame B of the machine.

D is the doffer, mounted upon the shaft D', 40 and S is the stripping-brush.

Upon the shaft of the main cylinder are mounted the usual loose pulley, a, and fast pulley b, whereby the cylinder is revolved when the engine is at work. The loose pulley a is provided with a groove to receive a band, c, which drives a pulley, d, attached to or connected with the ordinary pinion, e. The said pinion gears with the usual wheel, f, fixed upon the shaft D' of the doffer D. A 45 second pulley, g, is attached to or formed in

one piece with the said pulley d, and this second pulley drives the stripping-brush S by means of a band, h. We do not, however, wish to confine ourselves to this method of driving the stripping-brush.

When the main cylinder is to be stripped, the driving-strap is removed from the ordinary pulley, i, by which the doffer is driven during the working of the engine, and the band c is applied to its pulleys, as represented 55 in the drawings. When, therefore, the ordinary driving-belt is shifted from the fast pulley b onto the loose pulley a, the doffer will be revolved.

An important advantage arising from this 60 method of changing the actuation of the doffer is that the principal parts of the mechanism are always in position upon the carding-engine, so that it is only necessary to make the required changes in the connecting belts 65 or bands.

In order to drive the main cylinder at a reduced speed corresponding with the surface speed of the doffer, any suitable means may be used; but in all cases it is preferable to 70 drive the main cylinder from the doffer. A simple means for driving the main cylinder from the doffer is illustrated in the aforesaid British Patent No. 10,881 of 1884; but we prefer to use the devices which form the subject 75 of a separate application for United States Patent filed by us February 23, 1888, Serial No. 264,975, and which we will now describe briefly in connection with Figs. 3, 4, and 5 of the drawings.

On the other side of the carding-engine from the pinion e and wheel f the doffer-shaft D' is geared to a longitudinal side shaft, k, by means of bevel-wheels l, as usual. This side shaft, k, is mounted to turn in brackets 80 p p', and is provided with a worm, o, adapted to engage with a worm-wheel, m, on the axis of the main cylinder. In practice we prefer to form the ordinary belt-pulley, n, with teeth to form this worm-wheel, by which means a 85 special extra wheel is thus dispensed with. The shaft k is so mounted in its bearing-brackets p p' that it can be moved laterally, as is usual, in order to withdraw the bevel-pinion q from gear with the wheel r when 90

the feed-rollers are stopped. For this purpose the sockets p p' , and more particularly the latter, are elongated, as shown in the sectional view, Fig. 5. When the gears q r are 5 to be kept in engagement, the shaft k is held up to the inner end of the slot in the socket p' by means of a pin, s , as will be readily understood. When this pin is withdrawn and the shaft moved laterally in the socket, the 10 worm o is disengaged from gear with the worm-wheel m . In order to then keep the worm out of the way during the ordinary working of the engine, the said worm is slid upon the shaft entirely away from the wheel n and to 15 toward the socket or bearing p' . Preparatory to the stripping operation, either the pinion q is removed from the shaft, so as to stop the revolution of the feed-rollers, or the lap is withdrawn from between the rollers, so as to 20 stop the feed in that way. The worm is then slid along the shaft until it is in its operative position, as represented in Figs. 3 and 4. The worm o bears against a shoulder, k' , on the shaft k , and the action of the worm tends 25 to keep it up against this shoulder. The shaft is provided with a fixed key adjacent to the shoulder at the point occupied by the worm when in its operative position, so that the worm is caused to revolve with the shaft. 30 The driving-belt is now shifted onto the loose pulley, so that the main cylinder will cease to revolve at its working speed, but will re-

ceive a slow rotary motion through the medium of the said worm and worm-wheel.

We claim as our invention—

1. The combination of the main cylinder and doffer-cylinder of a carding-engine with fast and loose pulleys on the main cylinder-shaft, a pulley, d , for driving the doffer-cylinder, a belt or band connecting the said 40 loose pulley with the pulley d , and means, substantially as described, for driving the main cylinder at a speed to correspond with the surface speed of the doffer, all substantially as set forth. 45

2. The combination of the main cylinder and doffer-cylinder of a carding-engine, and mechanism, substantially as described, whereby the doffer-cylinder is geared to the main cylinder to impart a slow motion thereto, with fast and loose pulleys on the main cylinder-shaft, a pulley, d , for driving the doffer-cylinder, and a belt or band connecting the said 50 loose pulley with the pulley d , all substantially as set forth. 55

In testimony whereof we have signed our names to this specification in the presence of two subscribing witnesses.

GEO. ASHWORTH.
ELIJAH ASHWORTH.
